UNITED STATES PATENT OFFICE.

FRANZ RUDERT, OF HALLE-SAALE, GERMANY.

FASTENING DEVICE FOR RAILS.

Application filed March 28, 1927, Serial No. 179,090, and in Germany September 3, 1924.

My invention relates to improvements in the construction of railroad tracks for secondary railroads, such as used e. g. in mining, quarrying excavating on open workings 5 for lignite, mica, asbestos, tin, copper and other minerals and also in building harbours, canals, roads, embankments etc.

Railroad tracks of this character are bound to be frequently shifted obliquely to 10 their main direction, so as to provide new places of operation for the machines, excavators, dredgers and the like and also for the rolling stock carried on said tracks.

The primary object of my invention is to 15 provide a simple and effective device for fastening the rails of railroads of the type set forth which is designed in such wise that the rails are unimpeded to move relatively to the clamps by which they are secured to 20 the ties while the track is shifted.

In other words the ties must be free to occasionally move from their initially rectangular position to the rails into a more or less oblique position but without causing the 25 fastening elements to become loosened or damaged.

Another object of the invention is to design the fastening device in such wise that its component parts will be held securely in 30 their place in the tie or in a base plate fixed to the latter independently of the rail proper.

A further object of the invention is to 35 design the fastening device in such wise that it can be easily detached from the ties in the shortest possible time and even with the most primitive tools as crow bars, chisels etc., which is most important in cases when the whole railroad track must be taken to 40 pieces in order to be transferred over a considerable distance to a new place of operation.

The nature and scope of my invention is 45 briefly outlined in the appended claims and will be more fully understood from the following specification taken together with the accompanying drawing in which

Fig. 1 is a cross section through a railroad rail showing the improved fastening device in side elevation;

Fig. 2 is a cross section through the tie plate showing the fastening device in front elevation;

Fig. 3 is a plan view;

Fig. 4 is a perspective view showing salient features of the U-clamp, which forms

one of the main elements of the fastening device;

Fig. 5 is a cross section through the U-clamp taken in plane I—I indicated in Fig. 4;

Fig. 6 diagrammatically illustrates a railroad track of the type set forth during the shifting operation.

I propose to secure the rail S to the metallic tie proper or to the base plates a fastened to the metallic or wooden ties by means of U-shaped clamps b and wedges f of special design. The clamps b are provided with a lower hook or claw c which engages the tie a from underneath and an upper claw d which snugly fits over the flange of the rail but without firmly clamping the latter—to the tie plate.

According to this invention the clamps b are formed with convex shaped faces b² at 75 their inner side, viz. opposed to the foot of the rail, the form and location of said faces b² being more clearly visible in Figs. 4 and 5.

The clamps b on being inserted with their shanks into rectangular holes of the tie plate 80 a are carried thereon by means of laterally projecting shoulders b³, b⁴.

According to this invention the clamps b are formed at their rear side with sloping faces i the wedge like character of which 85 being indicated in Fig. 1 by vertical guide lines.

Conformably thereto the spikes f are provided with wedge shaped faces h at their inner side, so as to bear upon the rear faces 90 i of the clamps, whereas the outer faces of the spikes f will extend in substantially vertical direction so as to bear against the corresponding walls of the holes in the tie plate a.

As seen in Fig. 1 the clamps b and the spikes f are securely held in their proper place solely by the tie plate a and without any cooperation on the part of the rail.

According to this invention the spikes f 100 are formed with a projecting nose g provided preferably at their front side which prevents the spike being driven down too far into the hole of the tie plate; thus automatically a clearing space for the insertion of 105 tools for extracting the spikes is provided between the projecting head of the spike f and the tie plate a.

I prefer to form the spikes f at their top 110 with lugs m outwardly extending from the

shank of the spike at the front and laterally at both sides as seen in Figs. 1-3.

Tools of a primitive character as crow bars, chisels may be used for detaching the spikes by engaging any one of the various lugs *m*. The dismounting of the whole railroad track is thus greatly facilitated, whenever said track must be taken to pieces for transferring it over a considerable distance 10 to new quarters.

In cases when the track must be shifted obliquely to its main direction over a comparatively short distance—which is often performed with power driven shifting machines—the railroad track will repeatedly be 15 forcibly bent so as to assume a position shown in dotted lines in Fig. 6.

By reason of the specific construction of the U-shaped clamps *b* and the spikes *f* which, although securing the rail to the tie 20 or tie plate respectively, do not firmly clamp the rail and allow it to move longitudinally and angularly, any distortion and the breaking of the fastening members frequently experienced heretofore is eliminated.

It is obvious that various modifications may be made in the design of the component parts of the fastening device described above without substantially departing from the 25 scope of the appended claims and without

deviating from the spirit and the gist of my invention.

What I claim is:

1. A rail fastening device comprising a U-shaped clamp and a spike cooperating therewith for the specific purpose set forth, characterized therein that the clamp is provided with a convex shaped face at its inner side opposed to the foot of the rail. 35

2. A rail fastening device for the purpose 40 set forth and having the features outlined in claim 1, characterized therein that the U-clamp is provided with a wedge shaped face at the rear for cooperation with a corresponding wedge shaped face of the spike. 45

3. A rail fastening device for the purpose set forth and having the features outlined in claim 1, characterized therein that the spike is formed with a lug projecting from the shank of the spike underneath the spike 50 head.

4. A rail fastening device for the purpose set forth and having the features outlined in claim 1, characterized therein, that the spike head is formed with extensions laterally at both sides and at the front. 55

In testimony whereof I have signed my name to this specification.

FRANZ RUDERT.
